INKING DEVICE FOR TYPEWRITERS

Enrique Cereceau, Cordoba, Argentina

Application March 17, 1948, Serial No. 15,409

9 Claims. (Cl. 197—37)

1

The present invention is concerned with improvements in typewriters, and the chief object is to provide a typewriter with typeholders which are jointed at the ends of the corresponding supporting arms.

Another object of the present invention is to provide typeholders with means capable of bringing about the rotation of same, from an end position which corresponds to an inking roller, to a second position corresponding to a cylinder or platen.

A further object of the invention is to equip a typewriter with an inking roller divided into a plurality of sections, so that each section may rotate independently in the inside of a receptacle containing ink or similar marking fluid.

Other objects and advantages of the present invention will appear from the detailed description hereinafter set forth.

In order that the invention may be more clearly understood there will now be described with reference to the accompanying drawings, a preferred embodiment thereof which is given by way of example only and not by way of limitation.

In the drawings:

Fig. 1 is a schematic representation of a machine including the inherent characteristics of the invention;

Fig. 2 illustrates a mechanism connected to one typeholder, which is shown in its two extreme positions;

Fig. 3 is a schematic representation of a typeholder in its lower final position, in which a type carried thereby lies in contact with an inking roller;

Fig. 4 is a similar view of the typeholder in which it is shown in its upper position with a type lying in contact with the cylinder or platen, and

Fig. 5 is a section taken along line A—A of Fig. 3.

The machine, in its general construction and as shown in Fig. 1, is essentially constituted of the following means:

(a) Type elements associated with means arranged to bring about actuation of the same;

(b) Type-inking means;

(c) Cylinder or platen.

As illustrated in Figs. 2 to 5, the writing element is constituted by a typeholder 1, which forms an integral part of a projection 2, by means of which the same is rotatably disposed at the bifurcated end 3 of an arm 4.

The projection 2 is pivoted on a pin 5 which passes through both arms of the bifurcated end 3, and is provided with an opening 6 in which acts a trigger 7, this latter having an integral

2

sliding member 8, conveniently located in a guide formed in the corresponding arm 4, as shown in Figs. 3 to 5.

Fig. 2 shows one method by means of which the arm 4 may be moved, in which said arm is pivoted at an intermediate point of its length on a pivot pin 9, which forms an integral part of the frame of the machine.

In turn, the said arm 4 has at the opposite end to the typeholder 1, a slot 10 in which is disposed a small stem 11, said stem being solid with projection 12 which forms an integral part of an arm 13, which is pivoted, at one of its ends, on a shaft 14, while at the opposite end is applied the key 15 for the manual movement of the type.

On pressing said key the arm 4 passes from the position represented by the full line in Fig. 2, to that indicated by the dotted line in the same figure, thus producing angular rotation of the typeholder around pin 5.

Said angular rotation is produced as a result of the sliding member 8 acting on the fixed abutment 16, rotation in the opposite direction being produced when the sliding member comes in contact with the fixed abutment 17.

When the sliding member 8 operates on the abutment 17, the typeholder 1 is placed in contact with the inking roller, which, as will be observed from Fig. 1, is made up of a series of elements 16 mounted rotatably on a shaft 19, and dipping into marking fluid in the inside of a trough 20.

When the sliding member 8 operates on the abutment 16, the typeholder 1 comes into contact with the platen, which has been indicated in Figs. 2 and 4 by the reference numeral 21.

As what is represented and described is given as merely an explanatory example and not by way of limitation it is evident that modifications of construction and detail may be introduced without departing from that which, as a characteristic, is claimed in the claims which follow this description.

I claim:

1. In a typewriter having a rotatable platen and type arms oscillatable from a position of rest to a work position adjacent the platen, typeholders pivoted on the outer ends of the type arms for approximately 90 degrees oscillation, an inking device adjacent the rest position of the type arms, a fixed abutment adjacent the rest position of the type arms, and means carried by the type arms and cooperating with the fixed abutment for swinging the typeholders into alignment with the type arms and into contact with the inking device as the type arms approach the rest position.
2. In a typewriter having a rotatable platen

and type arms oscillatable from a position of rest to a work position adjacent the platen, type-holders pivoted on the outer ends of the type arms for approximately 90 degrees oscillation, an ink receptacle adjacent the rest position of the type arms, a partially exposed roller mounted in said ink receptacle, a fixed abutment adjacent the rest position of the type arms, and means carried by the type arms and cooperating with the fixed abutment for swinging the typeholders into alignment with the type arms and into contact with said roller as the type arms approach the rest position.

3. In a typewriter having a rotatable platen and type arms oscillatable from a position of rest to a work position adjacent the platen, type-holders pivoted on the outer ends of said type arms for approximately 90 degrees oscillation, a fixed abutment adjacent the platen, a second fixed abutment adjacent the rest position of the type arms, an inking device adjacent the rest position of the type arms, and means carried by the type arms and cooperating with the first fixed abutment for swinging the typeholders into a position at right angles to the type arms as the latter approach the platen and cooperating with the second fixed abutment for swinging the typeholders into alignment with the type arms and into contact with the inking device as the type arms approach the rest position.

4. In a typewriter having a rotatable platen and type arms oscillatable from a position of rest to a work position adjacent the platen, type-holders pivoted on the outer ends of said type arms for approximately 90 degrees of oscillation, a fixed abutment adjacent the platen, a second fixed abutment adjacent the rest position of the type arms, an ink receptacle adjacent the rest position of the type arms, a partially exposed roller mounted in said ink receptacle, and means carried by the type arms and cooperating with the first fixed abutment for swinging the typeholders to a position at right angles to the type arms as the latter approach the platen and cooperating with the second fixed abutment for swinging the typeholders into alignment with the type arms and into contact with said roller as the type arms approach the rest position.

5. In a typewriter having a rotatable platen and type arms oscillatable from a position of rest to a work position adjacent the platen, type-holders pivoted on the outer ends of said type arms for approximately 90 degrees oscillation, said typeholders each having a cam surface therein, a fixed abutment adjacent the platen, and slidable cam triggers in engagement with the cam surfaces in the typeholders and carried by the type arms and cooperating with the fixed abutment for swinging the typeholders into a position at right angles to the type arms as the latter approach the platen.

6. In a typewriter having a rotatable platen and type arms oscillatable from a position of rest to a work position adjacent the platen, type-holders pivoted on the outer ends of the type arms for approximately 90 degrees oscillation, said typeholders each having a cam surface therein, an inking device adjacent the rest position of the type arms, a fixed abutment adjacent the rest position of the type arms, and slidable cam triggers carried by the type arms in engagement with the cam surfaces in the typeholders and cooperating with the fixed abutment for swinging the typeholders into alignment with the type arms and into contact with the inking

device as the type arms approach the rest position.

7. In a typewriter having a rotatable platen and type arms oscillatable from a position of rest to a work position adjacent the platen, type-holders pivoted on the outer ends of the type arms for approximately 90 degrees oscillation, said typeholders each having a cam surface therein, an ink receptacle adjacent the rest position of the type arms, a partially exposed roller mounted in said ink receptacle, a fixed abutment adjacent the rest position of the type arms, and slidable cam triggers carried by the type arms in engagement with the cam surfaces in the typeholders and cooperating with the fixed abutment for swinging the typeholders into alignment with the type arms and into contact with said roller as the type arms approach the rest position.

8. In a typewriter having a rotatable platen and type arms oscillatable from a position of rest to a work position adjacent the platen, type-holders pivoted on the outer ends of said type arms for approximately 90 degrees oscillation, said typeholders each having a cam surface therein, a fixed abutment adjacent the platen, a second fixed abutment adjacent the rest position of the type arms, an inking device adjacent the rest position of the type arms, and slidable cam triggers carried by the type arms in engagement with the cam surfaces in the typeholders and cooperating with the first fixed abutment for swinging the typeholders to a position at right angles to the type arms as the latter approach the platen and cooperating with the second fixed abutment for swinging the typeholders into alignment with the type arms and into contact with the inking device as the type arms approach the rest position.

9. In a typewriter having a rotatable platen and type arms oscillatable from a position of rest to a work position adjacent the platen, type-holders pivoted on the outer ends of said type arms for approximately 90 degrees oscillation, said typeholders each having a cam surface therein, a fixed abutment adjacent the platen, a second fixed abutment adjacent the rest position of the type arms, an ink receptacle adjacent the rest position of the type arms, a partially exposed roller mounted in said ink receptacle, and slidable cam triggers carried by the type arms in engagement with the cam surfaces in the typeholders and cooperating with the first fixed abutment for swinging the typeholders into a position at right angles to the type arms as the latter approach the platen and cooperating with the second fixed abutment for swinging the typeholders into alignment with the type arms and into contact with said roller as the type arms approach the rest position.
